TUBULAR CASE AND IN PARTICULAR
LIPSTICK CASE

Pierre Kullmann, Paris, France

Application June 8, 1949, Serial No. 97,738
In France June 25, 1948

4 Claims. (Cl. 206—56)

1

The present invention relates to tubular cases and more especially lipstick or other cosmetic cases having a lid intended to be automatically operated, for opening or closing thereof, in response to rotational displacements of an element mounted inside the case, and in particular of the tube which serves to operate the outward and inward movements of the cosmetic (lipstick) with respect to said case.

The object of my invention is to provide a tubular case of this kind which is better adapted to meet the requirements of practice than those existing up to now and in particular which ensures a simple and reliable operation of the lid.

For this purpose, according to my invention, the lid, pivoted to the cylindrical body of the case about a line parallel to the axis thereof, is given at least its opening or its closing movement through the action of cooperating means provided on said lid and said body, and including a cam carried by one of the two last mentioned elements, adapted to rotate said lid, in response to an annular displacement of the inner tube in said body.

Preferred embodiments of my invention will be hereinafter described with reference to the accompanying drawings, given merely by way of example and in which:

Fig. 1 is a perspective view, with parts cut away, of a lipstick case made according to a first embodiment of my invention;

Figs. 2 and 3 are plan views of the lipstick case of Fig. 1, corresponding to two different positions of the lid;

Fig. 4 is a perspective view of two elements of a lipstick case made according to another embodiment of my invention;

Fig. 5 is a sectional detail view in a radial plane of the two elements shown by Fig. 4 illustrating an intermediate step of the assembly of these elements;

Fig. 6 is a horizontal part section of the structure of Fig. 4.

The lipstick case shown by the drawings includes a cylindrical body 1, a coaxial tube 2 fixed with respect to this body on the inside thereof and provided with a helical groove 3, a tube 4 coaxial with tube 2 on the inside thereof, this tube 4 being provided with a longitudinal groove 5 extending along a generatrix of said tube 4, a base 6 rigid with tube 4 and rotatable with respect to body 1, and finally a tube 7 coaxial with tube 4 on the inside thereof and provided with a lug 9 engaged in both of the grooves 3 and 5, this tube 7 carrying the lipstick 8.

It will be readily understood that rotation of

base 6 with respect to body 1 causes tube 7 and the lipstick fitted therein to move with a helical movement in body 1, whereby the lipstick can be moved out from said body or retracted thereinto.

The lid 11 of the case is freely pivoted to body 1 through a pivot pin 10 parallel to the axis of said body. Advantageously, as shown by the drawing, the top portion of body 1 is shaped to form a kind of annular housing 12, open at 13 and in which said lid 11 is housed when in the closed position, the inward flange 14 of this top portion 12 thus protecting said lid.

In order automatically to open and close lid 11 when the lipstick is moved out and retracted, respectively, I provide said lid 11 and tube 4 (which has a mere movement of rotation inside body 1) with cooperating cam and cam actuating means adapted to produce at least one of the opening and closing rotation movements of the lid in response to a predetermined rotation of tube 4 in the suitable direction.

For instance, as illustrated by the drawing, lid 11 is shaped to have a cam 15 carried by its under surface. On the other hand the top end of tube 4 is notched at 16 so as to have two longitudinal edges 17 and 20 at least one of which, for instance 17, is to constitute the cam actuating means intended to cooperate with cam 15.

Cam 15 is so shaped, and edge 17 so located that, at the beginning of the rotary movement of tube 4 which is to produce the outward displacement of lipstick 8, said edge 17 is in contact with the end of cam 15 and on the outer side of this cam, as shown by Fig. 3. It will be readily understood that rotation of tube 4 in an anti-clockwise direction will cause lid 11 to pivot about pin 10 to come into the position shown by Fig. 2, and this for a relatively small angle of rotation of tube 4. From this position on, as it results from Fig. 2, tube 4 can be further rotated in the anti-clockwise direction without exerting any kinematic action on cam 15 along which it slides tangentially.

It will be easy to devise the various elements so that the rotation of tube 4 from the position of Fig. 3 to that of Fig. 2 does not correspond to an upward displacement of tube 7 bringing lipstick 8 into contact with lid 11. For instance, as shown by the drawing, helical groove 3 ends, at the bottom, in a horizontal portion 18 such that, at the beginning of the rotation of tube 4, the lug 9 of tube 7 moves horizontally in this groove portion 18 and no upward movement is imparted to said tube 7.

Preferably, in order to hold the lipstick resili-

ently in the retracted position, the top edge of groove portion 18 is provided with a small projection 22 beyond which lug 9 has to be forced elastically to move it in one direction or the other. Thus, in the closed position, lug 9 is resiliently held by this projection 22 against the end of groove portion 18.

Closing of lid 11 may be obtained in either of two ways. According to one of these, the edge 20 of the notch 16 provided at the top end of tube 4 might be made to cooperate with the inner side of cam 15, so that clockwise rotation of tube 4 would close lid 11 by cooperation of said side of cam 15 with edge 20.

According to the preferred embodiment, as shown by the drawing, a spring 21 constantly urges lid 11 toward the closed position. Thus, as soon as tube 4, in the course of its clockwise rotation, passes through the position shown by Fig. 2, the outer side of cam 15 is kept applied against the edge 17 of this tube and at the end of this clockwise rotation the parts have been returned into the position of Fig. 3.

Spring 21 may for instance be constituted by an elastic metal wire wound about pin 10 and one of the ends of which is engaged in a housing provided in lid 11 whereas the other end is applied against a projection of flange 14.

It results from the above description that it is necessary accurately to secure tube 2 with respect to body 1. This can be advantageously obtained by means of either of two arrangements illustrated by the drawings.

In the embodiment of Fig. 1, body 1, which is of a substantial thickness, is provided, in its inner wall, with an annular groove 23 and with a short longitudinal groove 24. Tube 2 has, formed on the outer surface thereof, two projections 25 and 19, adapted to fit in said grooves, respectively. When elements 1 and 2 are assembled together, projection 19 is made to slide in rectilinear longitudinal groove 24. Inner tube 2 is just enough elastically deformable to enable projection 25 to slide along the inner wall of casing 1 and finally to drop into groove 23. Tube 4 is then securely held with respect to body 1 against axial displacement by the engagement of projections 25 in groove 23 and against rotary displacement by the engagement of projection 19 in groove 24, this last mentioned groove being suitably located to ensure proper cooperation of the edge 17 of tube 4 with cam 15.

In the embodiment of Figs. 4 to 6, body 1 is made of a thin metal sheet. In order to secure tube 2 in the desired position in said body, a notch 26 is cut off in the lower edge of tube 2 and the lower edge of body 1 has a small portion 27 thereof, of a width equal to that of said notch, folded inwardly substantially at right angles. When tube 2 is slipped in body 1, slight elastic deformations of the parts enable the bent portion 27 of body 1 to slide along the outer wall of tube 2. When the parts come into the desired relative position, this bent portion 27 engages into notch 26 and tube 2 is held in this position with respect to body 1.

In a general manner, while I have, in the above description, disclosed what I deem to be practical and efficient embodiments of my invention, it should be well understood that I do not wish to be limited thereto as there might be changes made in the arrangement, disposition

and forms of the parts without departing from the principle of the present invention as comprehended within the scope of the accompanying claims.

What I claim is:

1. A tubular case which comprises, in combination, an outer cylindrical body, a coaxial inner tube rotatable in said body, external means for rotating said tube with respect to said body, a lid transverse to said body pivoted thereto about a line parallel to the axis thereof, and a cam carried by the under face of said lid, said inner tube being provided at its upper part with a notch one side edge of which is adapted to cooperate with said cam for rotating said lid in one direction in response to rotation of said inner tube in said body in one direction.

2. A tubular case which comprises, in combination, an outer cylindrical body, a coaxial inner tube rotatable in said body, external means for rotating said tube with respect to said body, a lid transverse to said body pivoted thereto about a line parallel to the axis thereof, a cam carried by the under face of said lid, said inner tube being provided at its upper part with a notch one longitudinal edge of which is adapted to cooperate with said cam for opening said lid in response to rotation of said inner tube in said body in one direction, and spring means for urging said lid toward closed position.

3. A cosmetic case which comprises, in combination, an outer cylindrical body, a coaxial inner tube in said body provided with a helical groove, means for securing said tube in said body against both axial and rotary displacements therein, a second coaxial tube inside said first mentioned tube, said second tube being provided with a longitudinal groove, external means for rotating said second tube with respect to said body, a third tube for carrying said cosmetic, mounted coaxially in said second tube, a lug carried by said third tube engaged in both said helical and said longitudinal grooves, a lid transverse to said body pivoted thereto about a line parallel to the axis thereof and cooperating means on said lid and said second mentioned tube, including a cam carried by one of said two last mentioned elements, for rotating said lid with respect to said body in at least one direction in response to rotation of said second mentioned tube in said body in one direction.

4. A cosmetic case according to claim 3 in which said body is provided, in its inner wall, with an annular groove located in a plane at right angles to the axis of said body and with a longitudinal groove located in a radial plane of said body, the means for securing the first mentioned tube with respect to said body including two projections carried by the outer surface of said first mentioned tube and adapted to fit in said grooves respectively.
